ATTORNEY.

UNITED STATES PATENT OFFICE.

GILBERT DENNISON, OF HANDSWORTH, BIRMINGHAM, ENGLAND.

WATCH-FACE PROTECTOR.

1,169,935.

Specification of Letters Patent.

Patented Feb. 1, 1916.

Application filed March 1, 1915. Serial No. 11,345.

To all whom it may concern:

Be it known that I, GILBERT DENNISON, a subject of the King of Great Britain, and residing at Villa Road, Handsworth, Birmingham, in the county of Warwick, England, have invented certain new and useful Improvements in Watch-Face Protectors; and I do hereby declare that the following description of my said invention, taken in connection with the accompanying sheet of drawings, forms a full, clear, and exact specification, which will enable others skilled in the art to which it appertains to make and use the same.

15 This invention relates to improvements in watch face protectors and has for its object to provide an easily operable and simple protector.

20 Referring to the drawings:—Figure 1 is a plan of the complete watch face protector. Fig. 2 is a plan of the protector with the outer flanged cover removed, showing the segmental members. Fig. 3 is a plan of the flanged cover before fitting. Fig. 4 is a sectional elevation of Fig. 3. Fig. 5 is a plan of the fixed ring forming part of the protector. Fig. 6 is a sectional elevation on line X—X of Fig. 5. Fig. 7 is a plan of the slotted movable ring. Fig. 8 is a section on line Y—Y of Fig. 7. Fig. 9 is a plan of 25 one of the pivoted segmental members. Fig. 10 is a side elevation of Fig. 9. Fig. 11 is a sectional elevation of the face protector attached to a watch case.

30 35 In carrying this invention into practice as shown upon the accompanying drawings, the bezel of the watch case 1 which holds the watch glass 2 in position is provided with a small ridge 3 near its outer edge onto which 40 the protector is attached by snapping on, screwing on, or otherwise securing same in position.

45 The outside portion of the protector takes the form of a cover 4 which is shown at Figs. 3 and 4 and is preferably stamped out of sheet metal and provided with a center aperture. The side of said cover 4 is formed with a rim 5 which is milled or chased as desired for the purpose of assisting 50 its rotation by the finger and thumb.

55 Arranged to operate inside the case 4 is a fixed ring 6 as shown at Figs. 5 and 6 which is provided with a sharp upstanding rim 7 near its edge on one side only which is adapted to embrace the small ridge 3 of the watch glass bezel, the other side of the ring

6 being flat. In said ring 6 is provided four or more holes 8 equally spaced apart for the purpose hereinafter explained.

A movable ring 9 as shown in Figs. 7 and 8 is provided with four or more slots 10 to correspond with the holes 8 in the ring 6 and is secured by soldering or other suitable means to the inside of the cover 4.

Four or more segments 11 to correspond with the number of holes 8, as shown in Figs. 9 and 10 are cut out of hard sheet-metal and are provided at their ends with small projections, the projections 12 are turned up at right-angles to the segments 70 while the projections 13 are turned down at right-angles to the segments 11.

The aforescribed parts are now assembled in the following manner: The four segments 11 are pivoted by their downturned 75 projections 13 into the holes 8 in the fixed ring 6. The segments are then interlaced and disposed as seen in Fig. 2. The cover 4 with the ring 9 inside is then placed over the segments 11 and the ring 6 so that the 80 upturned projections 12 of the segments 11 engage with the slots 10 in the ring 9. The whole is then closed together by rolling the edge 14 of the cover 4 over the periphery of the fixed ring 6 carrying the segments 11 as 85 shown in Fig. 11.

The protector operates in the following manner: The projections 13 of the segments 11 are pivoted in the holes 8 of the stationary member or ring 6, this ring 6 is securely attached to the watch case 1 by means of the rim 7 engaging the bezel 3 of the watch case and is thereby held in position. The projections 12 of the segments 11 engage with the slots 10 in the ring 9. This ring 9 is secured to the outer cover 4 which revolves around the ring 6. When the cover 4 is revolved the projections 12 are moved with it and thereby the segments 11. Projections 100 13 on the other ends of the segments 11 are located in the holes 8 which act as a bearing. It will be seen from Figs. 1 and 2 that if the cover 4 is turned to the left the segments 11 will all move toward the ring 6 and if the cover 4 is turned far enough the segments 11 will lie on the said ring 6 and underneath the cover 4 clearing the aperture 15 and at the same time exposing the face of the watch. If the cover 4 is now turned to the right the segments 11 will be 105 brought into the position as shown in Figs. 1 and 2 and will thereby block the aperture 110.

15 and protect the face of the watch from damage.

The segments 11 are preferably domed in their centers so as not to bear on the watch 5 front.

I do not wish to limit the number of segments to four as more may be used if desired.

By this invention I provide an exceedingly 10 simple protector for the face of watches, more particularly for use with wrist watches.

What I claim as my invention is:—

1. A watch face protector, comprising in combination, a plurality of pivotal segmental members, a fixed ring for supporting one end of each of said members, a movable ring for supporting the other end of each of said members, and a flanged cover 15 rigidly secured to said movable ring the periphery of said flange being turned so as to engage with the periphery of said fixed ring, said rings being rotatable relative to each other by means of said cover so as to cause the pivotal members to cover or expose a watch case.

cause the pivotal members to cover or expose a watch face.

2. A watch face protector, comprising in combination, a plurality of interlaced pivotal segmental members, a fixed ring for supporting one end of each of said members, a slotted movable ring for supporting the other end of each of said members, and a flanged cover rigidly secured to said movable ring the periphery of said flange being turned so as to engage with the periphery of said fixed ring, said rings being rotatable relative to each other by means of said cover so as to cause the pivotal members to cover or expose a watch case.

In testimony whereof, I have signed my name to this specification in the presence of 20 two subscribing witnesses.

GILBERT DENNISON.
